UNITED STATES PATENT OFFICE.

JOHN BROUGHTON, OF BROOKLYN, NEW YORK.

REVERSIBLE LATCH.

SPECIFICATION forming part of Letters Patent No. 242,261, dated May 31, 1881.

Application filed September 20, 1880. (Model.)

To all whom it may concern:

Be it known that I, JOHN BROUGHTON, of the city of Brooklyn, in the county of Kings and State of New York, have invented certain 5 new and useful Improvements in Reversible Latch-Locks, of which the following is a specification.

My invention consists in the combination, in a latch-lock, with a lever and an independent 10 reversible latch-bolt, of a hook pivoted at one end to said lever and at the other end hooking onto the latch-bolt, and adapted to be disengaged from said bolt by lifting it in a plane parallel with the side plates of the lock-case.

15 It also consists in a novel means of holding and applying a spring which exerts a pressure upon the hook to hold it in engagement with the bolt.

In the accompanying drawings I have represented two different modifications, both of 20 which embody my invention. Figure 1 represents a view of a lock with the side plate of the case removed. Fig. 2 represents a section of a portion of the lock upon the dotted line 25 xx , Fig. 1. Fig. 3 represents a top view of the hook detached from other parts. Fig. 4 represents a view of a lock of slightly modified form, with the side plate of the case removed and the bolt in dotted outline partly withdrawn 30 from the case. Fig. 5 represents a section of a portion of the lock upon the dotted line yy , Fig. 4; and Fig. 6 represents a top view of the hook detached from other parts.

Similar letters of reference designate corresponding parts in all the figures.

35 In Figs. 1 and 4 I have represented a dotted outline of the locking-bolt in the lower part of the case; but this forms no part of my invention.

40 Referring first to Figs. 1, 2, and 3, which represent a lock in which the bolt is reversed by partly withdrawing it from the case and then turning it, A designates the latch-bolt, which has a round shank, a , fitting in a half-round bearing or guide, b , upon the case, and the collar c at its rear end. The said bolt is 45 also furnished upon opposite sides with notches d , the purpose of which will be hereinafter explained.

50 B designates the lever, which differs but little from those ordinarily used in locks of

this class; and C designates the hub, the wings e of which act upon the lever to operate it.

The bolt A is independent of the lever B—that is, it is not connected directly therewith, 55 but by a hook, D, of peculiar form, having at one end an eye, f , engaging with a teat or pin upon the lever, and at the other end a projection, g , which engages with one of the notches d in the bolt A. The hook engages with the 60 bolt by a transverse movement, and when not otherwise actuated is held in engagement with said bolt by a spring, h , acting upon a projection or lip, i , upon the hook, the spring fitting between said projection or lip and a lug, j , 65 projecting from the lever B and provided with a teat or pin for holding the spring in place. To reverse the bolt the hook must be lifted in a plane parallel with the side plates of the lock-case sufficiently to disengage its projec- 70 tion g from the notch d in the bolt, and the latter may then be pulled out or withdrawn from the case until the collar e strikes against the bearing or guide b . The bolt is then turned half round or reversed, and then pressed back 75 into the case until the end of the shank a strikes against the shoulder a' upon the hook, when the hook D, by the action of the spring h , will be pressed into engagement with the notch d .

The removable plate E of the case has in it a hole or aperture, k , through which any instrument, such as an awl, or even a splinter of wood or a pencil or the point of a screw, may be inserted into a depression or notch, l , in 85 the face of the hook D to raise the latter and disengage it from the bolt A. In order to prevent any dirt from getting into the case through the hole or aperture k , or the insertion of anything which would prove an obstacle to the 90 action of the lock, the hook is constructed so that it laps over the bolt and serves as a shutter or guard to cover the hole or aperture, as clearly shown in Fig. 2. The distance of the depression or notch l into which the instrument is inserted to lift the hook D from the pivot of the rod is so much greater than the distance from the said pivot to the spring h that a very slight force will serve to raise the 95 rod.

100 F designates a pivoted thumb-stop, which projects through the top of the case, and which

may be turned down so as to bear against a shoulder, *m*, upon the hook *D* when it is desirable to lock the latch-bolt.

When the lock is used as a mortise-lock the 5 hole or aperture *k* in the case is concealed within the mortise, thus preventing anything from being inserted to lift the rod *D*; and when said lock is used as a rim-lock the screw *n*, which aids in securing the lock to the door, is 10 inserted directly over the hook, as seen in Figs. 1 and 4; hence the hook cannot be lifted until the screw is taken out.

Referring now to Figs. 4, 5, and 6, which represent a lock in which the bolt is entirely 15 withdrawn from the case to reverse it, the bolt *A*, instead of having a round shank, as in the previously-described lock, has a flat shank, in which is a slot, *o*, which engages with a bearing or guide, *p*, in the case. To reverse 20 the bolt the hook *D* is lifted, as previously described, sufficiently to disengage its projection *g* (see Fig. 6) from the notch *d*, and the bolt is then withdrawn. After being reversed the bolt is thrust or pressed back into the case 25 until the shoulder *q* upon it strikes against the end of the hook, as shown in Fig. 4. When the bolt is withdrawn the hook *D* is held against downward movement by a pin or guard, *r*, upon which it rests.

30 The thumb-stop *F*, instead of engaging with the hook, as previously described in the lock shown in Fig. 1, engages with the end of the bolt *A*.

When constructed and held in place according 35 to my invention the bolt cannot drop out accidentally or be reversed by accident or mischief, and it will be seen that the lever and bolt are so connected that there is no lost motion between them.

40 I am aware that it is old to employ in a reversible latch-lock a bolt which is connected directly by a pin with the lever, and which may be disengaged from said pin by a movement sidewise.

45 I am also aware that it is old to connect a latch-bolt with a lever of peculiar form by in-

serting the bolt between jaws on said lever and retaining it there by means of a sliding locking-pin which may be moved longitudinally when it is desired to reverse the bolt. 50

I am also aware that it is old to employ in a lock a lever or yoke of peculiar form and a latch-bolt permanently connected therewith, the said lever being prevented from moving sufficiently to enable the bolt to be turned until one of the securing-screws of the lock is removed. 55

I am also aware that it is old to employ in a latch-lock a follower for transmitting movement from the lever to the bolt and a spring-actuated bell-crank lever which offers a resistance to an outward movement of the bolt sufficient to enable said bolt to be turned. 60

In none of the above-referred-to constructions is the bolt actuated from the lever by 65 means of a hook which is lifted to disconnect said bolt from said lever and leave it free to be drawn out and reversed, and I therefore do not claim them as of my invention.

What I claim as my invention, and desire 70 to secure by Letters Patent, is—

1. The combination, in a latch-lock, with a lever and an independent reversible latch-bolt, of a hook pivoted at one end to said lever and at the other end hooking onto said latch-bolt, 75 and adapted to be disengaged from said bolt by lifting it in a plane parallel with the side plates of the lock-case, substantially as specified.

2. The combination of the bolt *A*, the lever *B*, constructed with a lug or projection, *j*, the hook *D*, pivoted at one end to said lever and hooking at the other end onto said bolt, and the spring *h*, inserted between said lug or projection *j* and said hook *D*, and serving to resist the lifting of said hook, substantially as 85 specified.

JOHN BROUGHTON.
